LOCOMOTIVE TENDER

William C. Meyer, Altoona, Pa., assignor to The Pennsylvania Railroad Company, Philadelphia, Pa., a corporation of Pennsylvania

Application July 17, 1936, Serial No. 91,154

6 Claims. (Cl. 105—231)

This invention relates to streamlined locomotive tenders, and more particularly to the superstructure of such tenders and the manner in which storage tank openings are rendered accessible through the exterior streamlined casing.

As set forth in the co-pending application of Raymond G. F. Loewy and Harold A. Nonemaker, Serial No. 91,152, filed July 17, 1936, there are a number of advantages to be derived from the scientific streamlining of locomotives. These advantages are best realized when the tender used in conjunction with the locomotive is also streamlined in conformity with the contour of the locomotive, the exposed surfaces of the boiler, cab and tender being substantially continuous and so formed as to create a minimum of disturbance of the atmosphere through which the train travels. In the streamlining of the locomotive tender, it is desirable to extend the side walls proper upwardly to the level of the cab roof and to shape such extensions in conformity with the cross sectional outline of the cab.

However, the provision of a streamlined casing extending upwardly from the side walls proper of the tender introduces a difficulty with respect to the accessibility of the filling openings of the storage tank. The water tanks of tenders are customarily filled by means of a spout which swings over the top of the tender to a position above the inlet to the storage tank to be filled. Due to a number of considerations, such as the presence of overhead wires in electrified territory, and the structural details of the water columns and spouts in general use, it is not desirable to extend the height of the spout, and it is unsafe to have an attendant stand at a level near the electric wires when filling the tanks.

Therefore, the main object of this invention is to overcome the above recited difficulties by the provision in a tender of a streamlined casing conforming to the cross sectional outline of the locomotive and having a readily movable section which permits the storage tanks to be filled at the customary level and without change in the construction of the wayside water spouts now in use.

Other objects and advantages of the invention will appear in the detailed description of a preferred embodiment thereof which follows, and which has reference to the accompanying drawings, whereof:

Fig. I shows a side elevation of a locomotive tender embodying the invention.

Fig. II shows a plan view of the locomotive tender shown in Fig. I.

Fig. III shows an enlarged plan view, partially

broken out, of a portion of the tender in the region surrounding a storage tank opening.

Fig. IV shows an enlarged cross sectional view, taken as indicated by the arrows IV—IV of Fig. II.

Fig. V shows an enlarged cross sectional view, taken as indicated by the arrows V—V of Fig. I.

Fig. VI represents a fragmentary sectional view on an enlarged scale, taken as indicated by the arrows VI—VI of Fig. V, and showing details of one of the tracks and rollers employed for guiding a movable section of the streamlined casing.

In the drawings, there is shown a locomotive tender which is of conventional form with regard to the running gear, underframe, and coal and water storage compartments, but which has a superstructure added thereto embodying the improvements of the present invention. The tender is provided with flanges 1 extending upwardly and inwardly in continuation of the side walls proper 2 of the tender and forming a partial streamlined covering. The curvature of the flanges 1 desirably conforms with the cross sectional outline of the streamlined locomotive with which the tender is associated, and preferably the flanges 1 are joined together at the forward end of the tender by a bridge portion 3, thus defining a U-shaped exterior casing with a longitudinal passageway formed between the two sides. Located within the tender is the usual storage tank 4, having filling openings 5 at each side normally closed by hinged covers 6.

Each of the extension flanges 1 forming the exterior casing for the superstructure of the tender has a movable section 7 adjacent to one of the filling openings 5. Such movable sections 7 have pairs of rollers 8 thereon guided for movement horizontally and transversely across the top of the tender by engagement with parallel tracks 9, which are curved downwardly at their extremities, as clearly shown in Fig. V, thus insuring a secure seating of the movable section 7 when it is in its normal position flush with the outer surface of the flange 1. The tracks 9, as clearly shown in Fig. VI, are in the form of channels and are supported by suitably spaced brackets 10. The rollers 8 are free to rotate about the stub shafts 11 which are attached to the framework of the movable section 7, and are secured in place by nuts 13 and washers 14. Each movable section 7 is provided with a number of stops 15, preferably in the form of angles, which seat against shoulders 12 at the top edges of the side walls proper 2 when the movable section is in its normal position substantially flush with the exterior surface of the flange 1. At its upper end, each movable section 7 is

provided with locking means in the form of latch bolts 16 movable by handles 17 engaging keepers 18 attached to the flanges 1 at each side of the movable section.

5 Each movable section 7 preferably comprises a framework built up of angle bars secured together by gusset plates 19 at the corners, the movable section 7 in its cross sectional outline being in the general form of a quadrant of a 10 circle.

10 When it is desired to gain access to a filling opening 5 for the purpose of cleaning or filling the storage tank 4, the corresponding movable section 7 is unlocked by disengaging the latch bolts 16 and is moved inwardly along the parallel tracks 9 to a position within the longitudinal passageway at the top of the tender just beyond the position shown in dot-and-dash lines in Fig. V. The cover 6 of the filling opening 5 to be used is 15 then swung rearwardly to the position indicated in dot-and-dash lines in Fig. V. When the movable section 7 has thus been moved inwardly beyond the filling opening 5, the tank 4 is readily accessible and may be filled in the customary 20 manner by the ordinary wayside water spout. The movable section 7 is returned to its normal position after closure of the cover 6 of the filling opening 5, by pushing the same along the tracks 9 outwardly until the stops 15 are seated against 25 the shoulders 12 at the side walls proper 2 of the tender. This seating of the movable section 7 is carried out by the gravitational thrust imparted by the downward curve of the tracks 9 at their extremities. The latch bolts 16 are then operated to lock the movable section, and when 30 locked the exterior surface of the section 7 merges with the adjacent surfaces of the flange 1 to form a smooth continuous exterior casing.

35 It will be apparent that a tender constructed according to the present invention gains the desired advantages with respect to streamlined contour, and at the same time renders the water tanks accessible in the customary manner. Therefore, no changes in the construction of 40 existing water spouts are required, and no additional hazards for the fireman or other filling attendant are created.

45 While one particular embodiment of the invention has been described in detail, it is to be understood that various modifications or changes 50 may be had with respect to the contour of the streamlined casing, the form of the movable section, and the manner in which it is operated, all without departing from the spirit of the invention 55 as defined in the annexed claims.

Having thus described by invention, I claim:

60 1. In a locomotive tender having side walls, flanges extending upwardly and inwardly from the top of the tender in continuation of said side walls to a point short of the longitudinal center line of said tender to form a partial streamlined covering for the tender with a passageway between said flanges, a storage tank disposed between said side walls and having a filling opening at the 65 roof of the tank and near the level of the top of the side walls, one of said flanges having a section movable horizontally from a position flush with the exterior surface of said flange to a position inwardly of said filling opening, and extending into said passageway, and means for locking said movable section in the first named position.

70 2. In a locomotive tender having side walls, flanges extending upwardly and inwardly from the top of the tender in continuation of said side walls to a point short of the longitudinal center

line of said tender to form a partial streamlined covering for the tender with a passageway between said flanges, a storage tank disposed between said side walls and having a filling opening at the roof of the tank and near the level of the top of the side walls, one of said flanges having a section movable horizontally from a position flush with the exterior surface of said flange to a position inwardly of said filling opening, and extending into said passageway, tracks extending inwardly from the side walls, rollers on the movable section engaging said tracks, and means for locking said movable section in the first named position. 5

3. In a locomotive tender having side walls, flanges extending upwardly and inwardly from the top of the tender in continuation of said side walls to a point short of the longitudinal center line of said tender to form a partial streamlined covering for the tender with a passageway between said flanges, a storage tank disposed between said side walls and having a filling opening at the roof of the tank and near the level of the top of the side walls, one of said flanges having a section movable horizontally from a position flush with the exterior surface of said flange to a position inwardly of said filling opening, and extending into said passageway, means for guiding such movement of said section, stops for limiting the outward position of the movable section, 20 and means for locking said movable section in the first named position. 25

4. In a locomotive tender having side walls, flanges extending upwardly and inwardly from the top of the tender in continuation of said side walls to a point short of the longitudinal center line of said tender to form a partial streamlined covering for the tender with an uncovered longitudinal central passageway between said flanges, a storage tank disposed between said side walls and having filling openings at the roof of the tank and near the level of the top of the side walls, said flanges having sections movable horizontally from positions flush with the exterior surfaces of said flanges to positions inwardly of 40 said filling openings and within said passageway, and means for locking said movable sections in the first named position. 45

5. In a locomotive tender having side walls, flanges extending upwardly and inwardly from the top of the tender in continuation of said side walls to a point short of the longitudinal center line of said tender to form a partial streamlined covering for the tender with a passageway between said flanges, a storage tank disposed between said side walls and having a filling opening at the roof of the tank and near the level of the top of the side walls, one of said flanges having a section movable horizontally from a position flush with the exterior surface of said flange to a position inwardly of said filling opening, and extending into said passageway, a covering for the filling opening, tracks at each side of the filling opening, and extending transversely of the tender, rollers on said movable section adapted for travel 60 along said tracks, and means for locking said movable sections in the first named position. 65

6. In a locomotive tender having side walls, flanges extending upwardly and inwardly from the top of the tender in continuation of said side walls to a point short of the longitudinal center line of said tender to form a partial streamlined covering for the tender with a passageway between said flanges, a storage tank disposed between said side walls and having a filling opening 70

at the roof of the tank and near the level of the top of the side walls, one of said flanges having a section movable horizontally from a position flush with the exterior surface of said flange to a position inwardly of said filling opening, and extending into said passageway, a covering for the filling opening, tracks at each side of the

filling opening, extending transversely of the tender and inclined downwardly at the ends thereof adjacent to the side walls, rollers on said movable section adapted for travel along said tracks, and means for locking said movable section in the first named position. 5

WILLIAM C. MEYER.
